UNITED STATES PATENT OFFICE.

ALBERT G. REDMOND, OF INDIANAPOLIS, INDIANA, ASSIGNOR TO JACOB RICHARD FRANCIS, OF FLINT, MICHIGAN.

FUEL-FEEDING SYSTEM.

Application filed October 20, 1923. Serial No. 669,669.

This invention relates to certain new and useful improvements in fuel feeding systems especially adapted to be used in connection with motor vehicles for feeding fuel from the low level tank to the charge forming device of the motor vehicle whereby a constant supply of fuel is pumped from the low level fuel tank to the fuel bowl of the charge forming device.

Another and further object of the invention is to provide a fuel feeding system which is automatic in operation, the piston of the pump controlling the electric circuit so that the circuit is made and broken by the movement of the piston.

Another and further object of the invention is to provide a fuel feeding system in which the fuel instead of being pumped to a supplemental reservoir disposed between the low level reservoir and the fuel bowl of the carburetor, is pumped direct from a low level reservoir to the fuel bowl of the carburetor, the construction of pump being such that the fuel is maintained under pressure in the fuel line pipe so that when the level in the fuel bowl of the carburetor drops, the pressure is released and fuel flows into the fuel bowl and at the same time the pump starts to operate so as to replenish the fuel used by the charge forming device.

Another and further object of the invention is to provide a fuel feeding system in which the pump is enclosed in a receptacle to collect the leakage or overflow from the pump, means being provided for conveying this overflow to the fuel bowl of the charge forming device.

Another and further object of the invention is to provide an electrical pump which is entirely automatic in operation, the speed of the pump being governed by the consumption of fuel used by the charge forming device.

Other and further objects and advantages of the invention will be hereinafter set forth and the novel features thereof defined by the appended claims.

In the drawings,

Figure 1 is a diagrammatic view showing the embodiment of my invention applied to a motor vehicle; and

Figure 2 is a vertical section through the pump and receptacle showing in elevation the connection with the charge forming device.

In the drawing 1 indicates a motor vehicle

mobile which is provided with an internal combustion engine 2 having an intake manifold 3 to which is connected a charge forming device 4 provided with a float chamber 5 in which is pivotally mounted a float 6 operating a needle valve 7 for controlling the inlet 8 through which fuel is supplied through a pipe line, as will be hereinafter fully described, from a low level fuel tank 9 which in practice is generally arranged at the rear of the motor vehicle as clearly shown. The above description is given so that the operation of my improved construction of fuel feeding system when applied to the ordinary type of automobile now in use can be readily understood.

Preferably disposed within the hood of the motor vehicle is a receptacle 10 in which is disposed a pump barrel 11 provided with inlet port 12 in its bottom controlled by an inlet valve 13. The pump is provided with an outlet nipple 14 controlled by an outlet valve 15, said nipple extending through the wall of the receptacle 10 having a pipe 16 connected thereto leading to the inlet of the fuel bowl of the charge forming device.

As herein shown the bottom of the pump rests on the bottom of the receptacle 10 and has connected thereto the fuel line pipe 17 which extends rearwardly of the vehicle into the main fuel supply tank 9. The nipple 14 is provided with an inlet 18 in communication with the receptacle 10, said inlet being controlled by a check valve 19, which allows fuel which accumulates within the receptacle to pass out through the inlet into the pipe 16 leading to the fuel bowl of the carburetor, which prevents fuel from being drawn from the receptacle 10 by the pump.

The upper end of the pump-barrel 11 is enlarged to receive a solenoid 20, the core 21 of which is in the form of a piston working in the pump barrel so that when the solenoid is energized, the piston is raised and when de-energized, the piston drops by its own weight so as to force the fuel from the pump barrel direct to the fuel bowl of the charge forming device and the speed of travel of the piston is determined by the consumption of fuel by the charge forming device.

The solenoid is arranged in electric circuit with a source of supply in the form of a battery 22 now generally in use in automobiles and the circuit is made and broken by the movement of the piston 21 of the

pump, the circuit being closed on the full length of the up stroke of the piston and being broken the full length of the down stroke of the piston so that the piston is raised 5 by the solenoid and allowed to drop by gravity in order that it will maintain pressure on the fuel within the pump barrel until it has reached its full down stroke, whereby the circuit will be completed and the pump piston 10 will be raised and when it reaches its full up stroke, the circuit will be broken and the piston drops by gravity.

Extending across the top of the receptacle 10 is a flexible diaphragm 23 carrying a contact 24 connected to the solenoid by a wire 25, the solenoid being grounded as shown at 26 and the battery being grounded as shown at 27. Arranged over the flexible diaphragm is a cover 28 which carries a fixed contact 29 20 adapted to be engaged by the movable contact 24 in order to complete the circuit so as to energize the solenoid.

In order to provide means for making and breaking the electric circuit so as to energize 25 and de-energize the solenoid, I provide a linkage operated by the movement of the piston 21 of the pump and while I have shown a particular construction of linkage which is similar to the linkage used in connection with 30 vacuum tanks, I do not wish to limit myself to this particular construction, as I am aware that various forms of linkage can be used without departing from the spirit of my invention.

35 The particular construction of linkage herein shown consists of a pivoted lever 30 which is provided with a ball 31 at one end adapted to engage the under side of the diaphragm 23 so as to flex the diaphragm sufficiently to force the movable contact 24 in engagement with the fixed contact 29.

40 The lever 30 has connected to its other end a link 31 which in turn is connected to a link 32 having a link 33 pivotally connected thereto, the links 32 and 33 being connected together by a spring 34, the free end of the link 33 being connected to a rod 35 connected to the upper end of the piston 21 as shown at 36.

45 By this particular construction of linkage for flexing the diaphragm in order to complete the electric circuit, as the link 33 moves upwardly past the center, the link 32 trips up and stays up until the link 33 falls below the center, whereby the electric circuit is closed the full up stroke of the piston and is broken the full down stroke of the piston.

50 The fuel that leaks past the piston in the operation of the pump is collected by the 55 receptacle 10 and I provide the receptacle 10 with an overflow pipe 37 which extends to the fuel bowl 5 of the charge forming device 4 so that any excess of fuel which accumulates within the receptacle 10 will flow 60 by gravity to the fuel bowl of the charge

forming device and be consumed by the charge forming device as in the ordinary manner, as so long as fuel is flowing through the pipe 37 to the charge forming device, the pump will fail to operate. The valve controlled inlet 18 allows the fuel which also accumulates in the receptacle 10 to flow through the pipe 16 into the fuel bowl of the carburetor, but as previously stated prevents the pump from sucking fuel from the chamber 10. 75

In the operation of a fuel feeding system, as herein shown and described, the fuel is pumped by the solenoid pump direct from a low level tank to the fuel bowl of the charge forming device and the movement of the 80 pump piston controls the electric circuit so that the fuel is only pumped as it is consumed by the charge forming device. As the piston of the pump drops by gravity after being raised by the solenoid, it forces the fuel and maintains the fuel under pressure into the fuel bowl of the charge forming device, the float construction of which is such that the inlet closes when the fuel level reaches a predetermined level within the fuel bowl of 85 the charge forming device so that it is impossible to flood the carburetor as the piston remains in its descending position when the inlet valve of the float chamber of the carburetor closes and continues its descent 90 when the valve opens to replenish the fuel.

95 As the circuit is broken through the full length of the down stroke of the piston, the piston by its own weight maintains the fuel under pressure and when the circuit is again 100 closed, and the piston reaches the bottom of the pump chamber, the piston is raised so as to suck fuel into the pump barrel or chamber from the low level fuel tank and when the piston reaches its upward stroke, the circuit is broken so as to release the piston and allow it to drop by gravity and as the pump 105 barrel is provided with the usual inlet and outlet check valves, the fuel feeding system continues to operate in proportion to the 110 amount of gasoline used by the charge forming device so that the full capacity of fuel is supplied to the charge forming device at all times and under all conditions.

115 By having the outlet of the pump chamber provided with a valve controlled inlet in communication with the receptacle in which the pump is disposed, if the carburetor leaks when the motor vehicle is idle, fuel will flow out of the receptacle through 120 the inlet of the outlet nipple into the bowl of the carburetor so that fuel will be maintained in the carburetor at all times and under all conditions.

125 What I claim is:-

1. In a fuel feeding system for motor vehicles, the combination with a main fuel supply tank, of a carburetor located in a plane above said tank having a fuel bowl provided with a float controlled inlet, a pump for 130

pumping fuel direct from the said main supply tank to the fuel bowl of said carbureter, said pump comprising a pump chamber and a piston movable therein for maintaining the fuel in the pipe line from said main fuel supply tank to said carbureter under pressure, a source of current, an electric circuit including a solenoid for raising said piston, means actuated by said piston for making and breaking said circuit, and a receptacle in which said pump is located having an overflow pipe leading to the fuel bowl of the carbureter.

2. In a fuel feeding system for motor vehicles, the combination of a main fuel supply tank, of a carbureter located in a plane above said tank, a receptacle located in a plane above said carbureter, a pump located in said receptacle, a pipe connecting said pump to the main fuel supply, said pump being provided with a valve controlled outlet nipple, a pipe connecting said nipple to said carbureter, said nipple being provided with a valve controlled inlet in communication with said receptacle and means for operating said pump.

3. In a fuel feeding device for motor vehicles, the combination with a main fuel supply tank, of a carbureter located in a plane above said tank having a fuel bowl provided with a valve controlled inlet, a receptacle located in a plane above said carbureter, a pump mounted within said receptacle comprising a pump cylinder and a piston movably mounted therein, a pipe line leading from the outlet of said pump to the bowl of said carbureter, said pipe line having a valve controlled inlet in communication with said receptacle, a pipe leading from the inlet of said pump to the main fuel supply tank, a source of current, an electric circuit including a solenoid for actuating said piston, an overflow pipe extending from said receptacle to the bowl of said carbureter and means actuated by the movement of said piston for intermittently making and breaking said circuit for pumping fuel from the main fuel supply tank direct to the bowl of the carbureter.

4. In a fuel feeding system for motor vehicles, the combination with a receptacle located in a plane above the charge forming device of the vehicle, of a tank located in a plane below the carbureter of said vehicle, an electric pump mounted within said receptacle having a pipe in communication with

the main fuel supply tank and an outlet pipe 55 in communication with the fuel bowl of the carbureter, an overflow pipe leading from said receptacle to the bowl of the carbureter, a source of current, an electric circuit including a solenoid for actuating the piston 60 of said pump and means actuated by the movement of the piston of the pump for making and breaking said circuit.

5. In a fuel feeding system for motor vehicles, the combination with a carbureter of 65 a vehicle, of a main fuel supply tank located in a plane below said carbureter, a receptacle mounted in a plane above said carbureter, an electric pump arranged in said receptacle having a supply pipe leading from the main 70 fuel supply tank and a delivery pipe leading to the carbureter, said pump comprising a pump chamber and a piston movably mounted therein, a source of current, and electric circuit including a solenoid for actuating said 75 piston, a flexible diaphragm arranged over said receptacle, a fixed contact arranged above said diaphragm, a contact carried by said diaphragm, a linkage arranged within said receptacle having a connection with the piston 80 of said pump for flexing said diaphragm for opening and closing the circuit for intermittently energizing and de-energizing said solenoid for raising said piston within the pump cylinder.

6. An electric pump for fuel feeding systems for motor vehicles, enclosed in a receptacle and having the delivery port thereof in communication with said receptacle and provided with an overflow for delivering fuel to 90 the carbureter of the motor vehicle, a source of current, an electric circuit including a solenoid for actuating the piston of the pump, a fixed contact and a movable contact opening and closing the circuit and a linkage actuated 95 by the piston of the pump for moving said movable contact.

7. A fuel feeding system for motor vehicles comprising a low level tank, a carbureter, an electric pump for feeding fuel directly from 100 said low level tank to said carbureter, a receptacle in which said pump is arranged and an overflow pipe leading from said receptacle to the bowl of the carbureter.

In testimony whereof I hereunto affix my 105 signature.

ALBERT G. REDMOND.
